US00D627358S

(12) **United States Design Patent**
Allo Allo et al.

(10) **Patent No.:** **US D627,358 S**
(45) **Date of Patent:** **** Nov. 16, 2010**

(54) **COMPUTER CASE**

(75) Inventors: **Bryan N. Allo Allo**, North Highlands, CA (US); **Richard Garret Mauldin**, Erie, CO (US); **Pawel A. Woloszyn**, 212 Porter St., Woodland, CA (US) 95695

(73) Assignee: **Pawel A. Woloszyn**, Woodland, CA (US)

(**) Term: **14 Years**

(21) Appl. No.: **29/346,189**

(22) Filed: **Oct. 28, 2009**

(51) **LOC (9) Cl.** **14-02**

(52) **U.S. Cl.** **D14/440**

(58) **Field of Classification Search** **D14/439, D14/432, 440, 441, 250, 363-367, 371, 314, D14/328, 336, 337, 308, 300-302, 498, 496, D14/135, 136, 156, 160-165, 167-168, 207, D14/215, 216, 501, 189, 502, 176; D3/257, D3/271.9, 200, 294, 903, 422, 258, 269, 201, D3/211, 202-205, 207-210, 215; D9/519, D9/668, 551, 715, 503, 420, 428, 680, 424, D9/504, 426, 429; D6/434, 432, 351, 440, D6/450, 467, 486, 303, 301; D7/540, 539, D7/334, 332, 606, 628, 402, 710, 901, 515, D7/510, 604, 301, 703, 702, 707, 511; 473/594, 473/571, 609, 280, 406, 570, 604; 273/144 B, 273/138.1, 456; 446/397, 484, 16, 73, 267, 446/473; 428/11; 206/776, 315.9, 457, 525, 206/315.91, 217; 229/122, 123.2; 220/4.25, 220/4.24, 660-662, 669, 675, 4.07, 913; D19/90, 82, 36, 42, 44, 77, 78, 85, 97; D21/519, D21/709, 713, 789, 794, 329, 588; D25/7, D25/10, 13, 19, 26; D99/30, 37; D30/160; 52/81.1, 222, 73, DIG. 1; D4/116, 137; D28/76, D28/78, 91, 91.1; D11/157, 131, 81; 15/104.94; 118/264; 427/242; 455/347; D10/6; D32/1; D29/107; 463/46; D16/227; D26/125; 426/106, 426/112, 415, 419, 87; 383/103; 294/169; 101/DIG. 40; D18/14; 312/7.1, 208.3; 235/61 R, 235/1 R, 1 D; 150/165; 160/127, 23.1, 238; 439/577; 156/245, 274.4, 292, 304.2, 309.6; 219/770**
